RAILWAY TRACK CIRCUIT APPARATUS

Paul N. Martin, Penn Township, Allegheny County, Pa., assignor to The Union Switch & Signal Company, Swissvale, Pa., a corporation of Pennsylvania

Application October 29, 1941, Serial No. 416,950

6 Claims. (Cl. 246—28)

My invention relates to railway track circuit apparatus, and it has particular reference to the organization of such apparatus into railway track circuits arranged to be highly sensitive to train shunts and involving a track relay and means controlled thereby for conditioning the track relay to be energized at one level or another according as the relay is picked up or released, respectively.

An object of my invention is the provision of novel and improved means for improving the shunting sensitivity of track circuits.

Another object is the provision of track circuits arranged to cause the track relay to be energized at either a pick-up or a holding level and incorporating means for shifting the track relay to its holding level immediately when the relay picks up.

A further object is the provision of means in a track circuit to avoid false operation of governed apparatus caused by a high resistance train shunt or by intermittent losses of train shunt while a train occupies a track section.

An additional object is the provision of track circuits arranged to utilize only a minimum of energy derived from the track circuit and incorporating another source of energy for assisting in creating in the track relay its pick-up energy level.

The above-mentioned and other important objects and characteristic features which will become readily apparent from the following description, are attained in accordance with my invention by utilizing a repeater relay of a track relay for controlling the usual functions controlled by a track relay, by conditioning the track relay to be energized normally at a relatively low holding level, and by providing means including a back contact of the track relay and a contact of the repeater relay for conditioning the track relay when released to be energized at a relatively high energy level sufficient to cause the relay to pick up.

I shall describe several forms of apparatus embodying my invention, and shall then point out the novel features thereof in claims.

In the accompanying drawing, Fig. 1 is a diagrammatic view illustrating one form of apparatus embodying my invention. Figs. 1a and 1b are diagrammatic views representing modifications of a portion of the apparatus represented in Fig. 1. Fig. 2 is a diagrammatic view showing another modification of the apparatus shown in Fig. 1. In each of the several views, similar refer-

ence characters have been employed to designate corresponding parts.

Referring to the drawing, the reference characters 1 and 1a designate the track rails of a stretch of railway track divided by the usual insulated joints 2 into a track section D-E. A suitable source of current, such as a battery 3, is connected through the usual current limiting resistor 4 across the rails 1 and 1a at one end D of the section, and a track relay, designated by the reference character TR, has its winding connected to the rails at the opposite end E of the section. The winding of relay TR comprises, as shown, two coils 5 and 6 and the track circuit normally includes coil 5, resistor 7 and a portion of coil 6 of relay TR. The parts are so proportioned that under the assumed normal conditions, relay TR is held energized at a level only slightly above its release level. This energy level normally present in relay TR I shall term the holding level of relay TR.

Associated with relay TR is a repeater or secondary relay TPR normally energized, as shown, over an obvious circuit including front contact 8 of relay TR and a suitable source of current, such as a battery 9. Relay TPR is slow to pick up and controls contacts 10 and 11 which may be used, as indicated, to govern functions such as signals, locks, etc. usually controlled by track circuit apparatus.

Relays TR and TPR cooperate in controlling the energy level created in the relay in the following manner: When relay TR is released, as when a train enters section D-E and shunts the relay, relay TPR also is released and an obvious circuit path comprising back contact 12 of relay TR and back contact 13 of relay TPR is completed. This circuit path shunts resistor 7 and connects the lower terminal, as viewed in the drawings, of coil 5 to the lower terminal of coil 6, thereby interposing additional coil turns of the winding of relay TR in the track circuit. Under the assumed conditions, when the shunt is removed from relay TR, energy from the track rails energizes both the added coil turns and the coil turns normally in the track circuit, and the parts are so proportioned as to cause an energy level above the pick-up energy level to be created in the relay. This energy level is sufficiently high to impart appreciable velocity to the armature structure before contact 12 opens so that the momentum of the armature together with the holding energy level in the relay windings will be sufficient to carry the armature up to its picked up position where it will be held by the holding

energy in the winding. Relay TR is thus caused to operate its armature abruptly to its picked-up position, whereupon back contact 12 immediately opens to shift relay TR from its pick-up to its hold-up level.

The apparatus just described is characterized by the fact that the pick-up circuit of relay TR includes its own back contact 12, hence when the relay picks up it is shifted immediately to its hold-up circuit. This arrangement has a marked advantage over the usual primary-secondary relay combinations wherein the pick-up circuit of the track relay is controlled over a contact of the secondary relay but not by a contact of the track relay itself. Thus, with the usual primary-secondary relay combinations, in the event that a high resistance shunt condition exists in an occupied section, the shunt resistance might be sufficiently high to be ineffective to prevent pick-up of the track relay when the relay is in its pick-up circuit. The track relay accordingly might pick up, and be held up at its pick-up level until the secondary relay operates not only to shift the track relay to its holding level, but also to interrupt the control established by the contacts of the secondary relay over the functions governed thereby. After operation of the secondary relay has shifted the track relay to its lower energy level, the track relay will release in response to the high resistance shunt, and when the secondary relay releases to again condition the track relay to create its higher energy level, the track relay might again pick up and hold up until the secondary relay again operates. In such an arrangement, it is thus possible to have both the track and secondary relays "pump," that is, alternately pick up and release, due to poor shunting conditions in a section of occupied track.

Apparatus arranged in accordance with my invention to incorporate a back contact of the track relay in its pick-up circuit functions in such manner that if relay TR is caused to pick up due to a high resistance shunt existing in an occupied section, the immediate transfer of the relay to its holding circuit will cause the relay to release immediately due to the high resistance shunt applied thereto. Should the high resistance shunt persist, relay TR might "pump," that is, pick up and release intermittently as long as the poor shunting conditions exist, but due to the relatively short intervals that relay TR closes its front contact 8 and the slow pick-up characteristics of relay TPR, relay TPR remains in its released position to maintain the proper control of its contacts and functions controlled thereby. When, however, the shunt is removed from the relay as by the train vacating the circuit, then relay TR picks up and is shifted to its holding circuit where it remains. Relay TPR accordingly picks up at the end of its slow pick-up interval and the apparatus is restored to its normal condition. It follows, therefore, that the apparatus arranged in accordance with my invention provides a novel and improved arrangement whereby a track relay is conditioned to be energized at one level when it is picked up, is conditioned to be energized at a higher level when it is released, and controls its own energy level in such manner as to avoid causing operation of the associated secondary or control relay in the event that high resistance or poor shunting conditions exist in the section.

The control of the energy level in relay TR, as represented in Fig. 1, is attained by shunting out

a resistor and by simultaneously interposing coil turns in the track circuit. Either feature may, however, be individually employed to control the energy level in the relay. For example, resistor 7 may be connected, as shown in Fig. 1a, between the lower terminals of coils 5 and 6, for limiting the current in these coils to a value such as to cause the lower or holding energy level to be created in the relay. Resistor 7 is shunted over the circuit path comprising back contacts 12 and 13 of relays TR and TPR, respectively, and when the resistor is shunted the current value in the relay may be increased to cause the higher or pick-up energy level to be created in the relay. In like fashion, coils 5 and 6 may be normally energized, as shown in Fig. 1b, at a value such that the holding level is created in relay TR, and when back contacts 12 and 13 of relays TR and TPR are closed, an additional coil 15 may be connected in the track circuit for creating an additional energization, when the train shunt is removed from relay TR, sufficient to raise the energy level in the relay to its pick-up value.

In a further modification, represented in Fig. 2, coils 5 and 6 of relay TR are energized from source 3 over the track rails at a level sufficient to create in the relay its holding energy level, and when back contacts 12 and 13 are closed, coil 15 is energized from a local source, such as a battery 9, at a level just below the pick-up level of the relay. Thus, when section D-E is occupied and relay TR is shunted, coil 15 is energized and maintains in the relay an energy level insufficient to pick up the relay, but sufficient when the shunt is removed and coils 5 and 6 become energized, to cooperate with the coils 5 and 6 in creating an energy level higher than the pick-up level of the relay. Relay TR of Fig. 2 accordingly will pick up when the shunt is removed from its windings 5 and 6, and when the relay picks up, its back contact 12 opens to place coil 15 on open circuit, thereby causing the energy level in the relay to be reduced to its holding level.

The arrangement represented in Fig. 2 incorporates back contact 12 of relay TR in its pick-up circuit, hence relay TR might be picked up and released due to the existence of high resistance or poor shunting conditions in the section, without causing operation of relay TPR and its associated control contacts 10 and 11. In addition, the track circuit apparatus represented in Fig. 2 is arranged to derive from the track circuit only the energy required to hold up the relay, and the additional energy required to raise the energization of the relay to its pick-up level is derived from a local source. This arrangement obviously enables the energization of the track circuit to be maintained at a minimum, thereby reducing the possibility of excessive ballast losses and enabling longer rail stretches to be incorporated into a track circuit.

Although I have herein shown and described only a few forms of railway track circuit apparatus embodying my invention, it is understood that various changes and modifications may be made therein within the scope of the appended claims without departing from the spirit and scope of my invention.

Having thus described my invention, what I claim is:

1. In combination, a source of electrical potential, a first relay, a circuit connecting a portion of the winding of said first relay to said source for normally creating in said first relay an energy level above its release but below its

pick-up level, a slow pick-up relay energized over a circuit including a front contact of said first relay for exerting a control dependent upon the position of said first relay, and a circuit including in series a back contact of said first relay and a back contact of said slow pick-up relay for connecting an additional portion of the winding of said first relay to said source, whereby to condition said first relay to create an energy level above its pick-up level.

2. In combination with a section of railway track provided with a source of current connected across the track rails at one end of the section, a track relay having a portion of its winding connected in circuit with a resistor across the track rails at the opposite end of said section for creating in said relay an energy level above its release but below its pick-up value, a slow pick-up control relay provided with an energizing circuit including a source of current and a front contact of said track relay, and a circuit including in series a back contact of said track relay and a back contact of said slow pick-up control relay and an additional portion of said relay winding, for shunting said resistor by a circuit path which connects said additional portion of said relay winding across the track rails, whereby to condition said track relay to create an energy level above its pick-up level.

3. In combination with a section of railway track provided with a source of current connected across the track rails, a track relay having a portion of its winding connected across the track rails for creating an energy level above the release but below the pick-up level of the track relay, a slow pick-up control relay energized over a control circuit including a source of current and a front contact of said track relay, and a circuit including in series a back contact of said track relay and a back contact of said slow pick-up control relay for connecting said portion of the winding of said track relay and an additional portion of the winding of said track relay across the track rails, whereby to condition said track relay to create an energy level above its pick-up level.

4. In combination with a section of railway track provided with a source of current connected across the track rails, a track relay having

its winding connected in circuit with a resistor across said track rails for creating in said track relay an energy level above its release but below its pick-up value, a slow pick-up control relay energized over a circuit including a source of current and a front contact of said track relay, and a circuit including in series a back contact of said track relay and a back contact of said slow pick-up control relay for shunting said resistor, whereby to condition said track relay to create its pick-up energy level.

5. In combination with a section of railway track provided with a source of current connected across the track rails, a track relay having a portion of its winding connected across said track rails for creating in said track relay an energy level intermediate the release and pick-up values of the track relay, a slow pick-up control relay provided with an energizing circuit including a source of current and a front contact of said track relay, and a circuit including in series a back contact of said track relay and a back contact of said slow pick-up control relay for energizing an additional portion of the winding of said relay with energy from a source of current, said two portions of the winding of said track relay being arranged to create additive fluxes whereby to condition said relay to create an energy level sufficient to cause said track relay to pick up.

6. In combination, a section of railway track having a source of current and the winding of a track relay connected across the rails at opposite ends of said section respectively, said winding energizing said relay at a level intermediate its pick-up and release levels, a slow pick-up control relay energized over a circuit including a front contact of said track relay, an additional winding for said track relay, an additional source of current, and a circuit including a back contact of said track relay and a back contact of said slow pick-up control relay for connecting said additional source to said additional winding, said two windings being arranged to create additive fluxes when energized, whereby to condition said track relay to create an energy level having a value exceeding its pick-up level.

PAUL N. MARTIN.
